UNITED STATES PATENT OFFICE.

JOHN JOSEPH CORNER, OF SOURIS, MANITOBA, CANADA.

SAFETY APPLIANCE FOR TRAINS.

1,259,963.

Specification of Letters Patent. Patented Mar. 19, 1918.

Application filed July 5, 1917. Serial No. 178,767.

To all whom it may concern:

Be it known that I, JOHN JOSEPH CORNER, of the town of Souris, in the Province of Manitoba, Canada, have invented certain new and useful Improvements in Safety Appliances for Trains, of which the following is the specification.

The invention relates to a safety appliance for trains and the principal object of 10 the invention is to provide an attachment which can be readily applied on a train of cars equipped with an air brake system and will automatically operate to set the brakes in the event of anything going wrong with 15 the track, road bed or running gear and by so doing will bring the train to a stop before a serious accident has occurred.

A further object of the invention is to construct the appliance in a regular, simple 20 and durable manner so that it can be easily and quickly applied on the cars and standardized.

With the above objects in view the invention consists essentially in the arrangement 25 and construction of parts hereinafter more particularly described and later pointed out in the appended claims, reference being had to the accompanying drawings in which:—

Figure 1 represents a side view of a train 30 of cars equipped with my invention.

Fig. 2 represents an enlarged detailed side view of the appliance as associated with a single truck.

Fig. 3 represents a plan view of the parts 35 appearing in Fig. 2.

Fig. 4 represents an enlarged detailed vertical sectional view of one of the discharge valves.

Fig. 5 represents an enlarged detailed 40 side view of a part of one of the brackets with members carried thereby and the adjacent valve rod.

In the drawings like characters of reference indicate corresponding parts in the 45 several figures.

In the following description I have not considered it necessary to the understanding of my invention to enlarge on the present air brake system as installed on trains 50 as this is well understood by those familiar with the art. The only point which is of value to me is that in such systems a drop in the pressure of the air in the air brake system operates to set the brakes with which 55 the train is equipped and in so doing stops the train.

In applying my invention to a train of cars I desire to equip the train so that if anything irregular occurs in the running gear of the train or if for any reason the 60 wheels are thrown from the track the irregularity will effect an operation which will automatically release the pressure in the air brake system and accordingly will set the 65 brakes.

While I have shown the invention as applied on two cars, still it will be understood that it will be applied on all cars of a train of cars and can be also installed on the locomotive and tender so that the entire train 70 is directly under the control of my system.

Referring now to the drawings:—

1 represents a locomotive, 2 a tender and 3 and 4 cars coupled to the locomotive, such constituting a train operating on the tracks 75 5. In the present systems the cars are equipped with an air brake system controlled by the engineer in the cab and extending throughout the complete length of the train of cars. In the drawings the main 80 air pipe line is indicated by the reference numeral 6 and in so far as this line pipe is concerned it is to be understood that any drop in the pressure of the air in the pipe line effects the setting of the air brakes. 85 As hereinbefore intimated I do not consider it necessary to enlarge on the manner in which the brakes are actuated through the drop in pressure in the pipe line as this is well understood and forms no part of the 90 present invention.

Associated with each of the trucks of the cars I provide the following parts.

7 and 2 represent pairs of parallel brackets passing lengthwise of the car trucks in 95 a location above the truck frame 9 and having their ends permanently secured to the underside of the car as indicated at 10. Each bracket carries a plurality of rocker bars 11, some singly hooked as indicated at 100 12 and others doubly hooked as shown at 13 and 14. The rocker bars are all mounted on centrally located pivot pins 15 extending from the sides of the bracket and the doubly hooked ones are associated with the car 105 wheels 16 while the singly hooked ones are associated with the other parts of the running gear such as the brake beams 17 and spring planks 18.

Adjoining the brackets I locate longitudinally disposed slidably mounted valve rods 19 and 20 which have their rear ends con-

nected in each instance to the levers 21 and 22 of similar air discharge valves 23 and 24 suitably carried from the underside of the car and in a location to the rear of the 5 trucks.

The valves 23 and 24 are both of similar construction and are of well known design. Each comprises a casing 25 inclosing an interior air chamber 26 in which operates a 10 valve 27 mounted on a vertically disposed valve stem 28 which is held normally pressed upwardly by a coil spring 29 bearing against the lower end of the stem and holding the valve normally seated or closed, against the 15 seat 30.

An outlet duct 31 is provided in the upper part of the casing which puts the chamber 26 in communication with atmosphere when the valve is unseated. An inlet 20 port 32 opens to the chamber 25 and is directly connected by means of a branch pipe 33 with the main pipe line 6 so that the air pressure in the interior of the casing is the same as the air pressure in the line pipe 25 when the valve is closed.

The upper end of the valve stem in each instance is positioned directly beneath the underside of the valve lever which it will be observed is provided with two similar 30 laterally disposed hooks 34 and 35 which are normally caught on stationary cross pins 36 and 37.

From this arrangement it will be obvious that the valve lever in either instance can be 35 rocked either forwardly or backwardly with the result that in either movement the underside of the said lever will strike the upper protruding end of the stem and force it down to release the valve from the seat 40 and bring the interior of the casing in direct communication through the port 31 with the atmosphere.

When this occurs a reduction of the pressure in the pipe line 6 will be effected, which 45 reduction will operate to set the train brakes in the well known way. At this point it is again mentioned that the rods 19 and 20 are connected to the upper ends of the levers.

Each rod is supplied with a plurality of 50 outstanding striker pins 38 which extend to the inner sides of the hooks of the rocker bars and are arranged so that when the rod is shifted it will effect the swinging of the rocker bars on their pivot points.

55 Referring now particularly to Fig. 5, it will be seen that the faces of the hooks which are adapted to engage with the striker pins are curved in a particular manner so that in the longitudinal shifting movement 60 of the rods the striker pins will not bind with the hooks but will engage with and ride on the faces of the hooks for an interval sufficient to allow of the movement of the rocker bars. The doubly hooked rocker 65 bars carry downwardly extending arms 39

which have their upper ends pivotally secured at 40 to the forward ends of the bars and their lower ends fitted with a pair of extension fingers 41 and 42 which span the axle of the adjoining wheel.

The singly hooked rocker bars carry at their forward end downwardly extending arms 43 pivoted to the rocker bars at 44 and having their lower ends supplied with a single extending finger 45 which is adapted 70 to pass beneath the brake beam in one instance and the spring plank in the other and in this connection, while I have shown the downwardly extending arms as associated with the brake beams and spring 75 planks, still I wish it to be understood that these could be supplied for any other part of the truck which is apt to break loose and fall and cause accident.

Considering a train of cars equipped with 80 this invention, it will be readily seen that should the wheels mount the rails or should the road bed be broken, to allow the wheels to drop, the brakes will be applied as either an up or a down movement of any wheel 85 axle will cause the fingers 41 or those 42 to be struck to effect either an up or a down movement in the bar 39. Any such movement produced in any one of these bars 39 will rock the rocker bar and cause one or 90 other of the striker pins associated with the hooks 13 and 14 to be shifted and they in shifting shift the valve rod and operate the valve lever to release the valve 27 thus reducing the pressure in the pipe line which 95 sets the brakes and stops the train.

The same action occurs should any such part such a brake beam or spring plank become loose and drop. In dropping it will hit the finger 45 which will effect through 105 the arm 43, the rocker bar, hook and striker pin, the shifting of the rod to manipulate the valve and reduce the pressure in the pipe line. Accordingly a train equipped with my invention is entirely controlled, 110 that is to say, no matter what may go wrong with the track, road bed or running gear any mishap will operate automatically to set the brakes and bring the train to a stop.

What I claim as my invention is:—

1. In a safety appliance for trains equipped with an air brake system, the combination with the air brake system and the trucks of the train embodying the axles, 115 brake beams and spring planks, of means for automatically effecting a reduction of pressure in the air brake system upon the occurrence of any irregular movement of the axles, brake beams and spring planks, said means being actuated by the irregular movement of any of such members.

2. In a safety appliance for trains equipped with an air brake system, the combination with the air brake system and the trucks of the train embodying the axles, 120

brake beams and spring planks, of an air discharge valve connected with the air brake system and means connecting the air valve with the truck in a manner such that 5 any irregular movement of either the axle, brake beam or spring plank will effect the automatic operation of the valve to reduce the pressure in the air brake system.

3. In a safety appliance for trains 10 equipped with an air brake system, the combination with the air brake system and the trucks of the train embodying the axles, brake beams and spring planks, of an air discharge valve connected with the air 15 brake system, a shiftable rod connected with the valve and passing to the truck, pivotally mounted hooked rocker bars disposed adjacent the rod, pins extending from the rod and adjoining the hooks, arms hanging from the rocker bars and fingers closely associated with the axles, brake beams and spring planks and carried by the arms and adapted in the irregular shifting of the 20 brake beams, axles and spring planks to effect the shifting of the rod and the release of the valve to reduce the air pressure of the air brake system.

25 4. In a safety appliance for trains

equipped with an air brake system, the combination with the air brake system and the trucks of the train embodying the axles, 30 brake beams and spring planks, of an air discharge valve connected with the air brake system, a shiftable rod connected with the valve and passing to the truck, pivotally mounted hooked rocker bars disposed adjacent the rod, pins extending from the rod and adjoining the hooks, arms hanging from the rocker bars and fingers closely 35 associated with the axles, brake beams and spring planks and carried by the arms and adapted in the irregular shifting of the brake beams, axles and spring planks to effect the shifting of the rod and the release of the valve to reduce the air pressure of the air brake system.

Signed at Souris this 26th day of May 1917.

JOHN JOSEPH CORNER.
